CONDENSER

Morris H. Bennett, Prospect, Conn., assignor to
 Scovill Manufacturing Company, Waterbury,
 Conn., a corporation of Connecticut

Application August 11, 1932, Serial No. 628,287

4 Claims. (Cl. 175—41.5)

The present invention relates to multiple plate air dielectric condensers, particularly though not exclusively adapted for use in radio circuits.

An object of the present invention is to provide improved means for holding and maintaining in predetermined position a group or a plurality of groups of stator plates.

Another object of the invention is to provide in connection therewith means for insulating the stator plates such that the leakage path is decreased while, at the same time, only a small amount of insulating material is employed in the electrostatic field.

A further object of the invention is to provide means for mounting the stator plates such that they can be adjusted into predetermined position with respect to cooperating rotor plates, the construction being such that it may be rapidly assembled, and, when assembled, maintains the stator plates rigidly in assembled position.

Other objects of the invention will appear from the following description taken in connection with the accompanying drawing which illustrates by way of example a preferred embodiment of the invention, and in which,—

Figure 1 is a top plan view of a portion of a gang condenser intermediate the ends thereof and showing a plurality of groups of stator plates mounted and held in position in accordance with the present invention;

Figure 2 is a vertical transverse sectional view on the line 2—2 of Figure 1;

Figure 3 is a perspective detail view on an enlarged scale, showing one of the holding plates;

Figure 4 is a fragmentary transverse sectional view of a modified form of the invention; and

Figure 5 is a fragmentary perspective view of part of one of the frame sides.

Referring in detail to the drawing, the condenser shown includes a channel member having a bottom 11 and sides 12. Three groups of stator plates with cooperating rotor plates are shown, though it will be understood that the number of groups and the number of plates in each group may be varied. Between each group of cooperating plates is a shield 14 secured to the channel member and preferably extending laterally beyond the side walls 12 of the channel member. The stator plates of each group are secured to a metal strip 16 by being staked thereto as shown in Figure 2 at 18. The metal strips 16 are each provided with a laterally projecting and longitudinally extending channel 20 and the vertical faces of these channels, in the embodiment of the invention herein illustrated, are provided with

a pair of spaced apart circular apertures having a smaller diameter than the diameter of balls 22 cooperating with these apertures. Secured to the sides 12 of the condenser frame or channel member are holding plates 24 which may be secured in position upon the channel member by screws 26 threaded in the side walls 12 of the channel member or condenser frame. The shanks of the screws 26 pass through openings 28 in the holding plates 24. These openings may 10 be circular or elongated and in any event are preferably larger when measured across their smallest dimension than the shanks of the screws 26, the heads 30 of the screws being large enough to hold the plates 24 to the condenser 15 frame.

The upper portion of each plate 24 as herein shown is provided with a pair of spaced apart circular apertures 32, whose diameter is less than the diameter of the balls 22, of insulating material.

As shown in Figure 2, the holding plates 24 bear against the balls 22 in line contact therewith, a portion of each ball entering its cooperating opening 32. Opposite the openings 32, the balls similarly enter partly in the openings, preferably circular, provided for them in the channel portion 20 of the stator plate mounting strip 16. As a result of the construction described, the insulating balls 22, which may be relatively small, 30 have circular line contact with the stator plate mounting strip 16 and with the holding plate 24. The parts are proportioned so that, when they are in the assembled position of Figures 1 and 2, the holding plates exert a pressure against the 35 insulating balls, this pressure being exerted by each plate 24 towards the other.

Referring to Figure 4, the frame is shown as a channel member having a bottom 11' and compression member sides 24'. The sides 24' are 40 preferably cut as shown in Figure 5 or otherwise to provide an arm 50, or pair of arms, provided with openings 32', similar to openings 32 and serving the same purpose. The balls 22' thus bear against the channel member 16' about the 45 edges of the ball openings in the channel portion 20'. The stator plates may be staked to the channel member 16' as indicated at 18'.

With this construction, compression is exerted as before, and, if necessary, the arms 50 may be 50 bent with respect to the frame to insure the desired compression and maintenance of the stator plate assembly or assemblies in predetermined position.

With the construction described, the leakage 55

path has been made relatively small while, at the same time, only a relatively small amount of insulating material has been employed; also assembly of the parts is relatively simple and can be accomplished with adjustment of the stator plates in their final predetermined position; further, the construction is such that compression is produced by the holding plates which are themselves rigidly mounted, so that each stator plate group when assembled is, in use, maintained permanently in predetermined position.

What is claimed is:

1. In a condenser, a frame having sides, a group of stator plates, a group of rotor plates interleaved therewith, and means for mounting the stator plates in the frame comprising opposed assembly members to which said stator plates are secured in permanent predetermined spaced relation to each other, each of said assembly members having a channel portion and each having spaced openings in the channel portion thereof, opposed holding plates adjustably secured to the frame sides and having openings therein spaced equally with and in cooperative relation to said first named openings, and insulating mounting devices each of which bears partly against the edge of an opening in the holding plate and partly against the edge of an opening in said assembly member, said insulating mounting devices being larger than their cooperating openings and extending partly into each of their cooperating openings, and said opposed holding plates exerting pressure towards each other through said insulating mounting devices and said stator unit.
2. In a condenser, a frame having sides, a group of stator plates, a group of rotor plates interleaved therewith and means for mounting the stator plates in the frame comprising opposed assembly members to which said stator plates are secured in permanent predetermined spaced relation to each other, each assembly member having a channel portion and each having spaced openings in the channel portion thereof, opposed holding plates adjustably secured to the frame sides and having openings therein spaced equally with and in cooperative relation to said first named openings, and insulating balls each of which bears partly against the edge of an opening in the holding plate and partly against the edge of an opening in the cooperating assembly member, the balls being of larger diameter than said openings and said opposed holding plates exerting pressure towards each other through said balls and said stator unit.
3. In a gang condenser, a frame having sub-

stantially parallel sides, a plurality of groups of stator plates, a group of rotor plates interleaved with each group of stator plates, and means for mounting each group of stator plates in the frame comprising a pair of channeled assembly members secured to said stator plates along opposite edges of said plates and holding said plates in permanent predetermined spaced relation to each other, each assembly member having at least two circular openings in the channel portion thereof, a holding plate for each channeled assembly member, each holding plate having a portion provided with screw receiving openings, screws in said openings of smaller diameter than said openings and adjustably securing the holding plate to the frame sides, each holding plate having an offset portion provided with a pair of circular openings spaced equally with and in cooperative relation to said first named openings, and insulating balls each of which bears partly against the edge of an opening in the offset portion of a holding plate and partly against the edge of an opening in the cooperating channeled assembly member, the balls being of larger diameter than said openings and said holding plates exerting pressure towards each other and against the stator plates, said pressure being through said balls and the channeled portions of said assembly members and said stator unit.

4. In a condenser, a frame having sides, a group of stator plates, a group of rotor plates interleaved therewith, and means for mounting the stator plates in the frame comprising opposed assembly members to which said stator plates are secured in permanent predetermined spaced relation to each other, each of said assembly members having a channel portion and each having spaced openings in the channel portion thereof, opposed holding plates adjustably secured to the frame sides and having openings therein spaced equally with and in cooperative relation to said first named openings, and mounting devices each of which bears partly against the edge of an opening in the holding plate and partly against the edge of an opening in said assembly member, said mounting devices being larger than their cooperating openings and extending partly into each of their cooperating openings, said opposed holding plates and mounting devices comprising insulation to insulate the stator from the frame, and said opposed holding plates exerting pressure towards each other through said mounting devices and said stator unit.

MORRIS H. BENNETT.
